CLAIM

The ornamental design for a cantilever mounted luminaire, as shown and described.

DESCRIPTION

FIG. 1 is a top perspective view of a cantilever mounted luminaire, showing my new design;

FIG. 2 is a bottom perspective view thereof;

FIG. 3 is a left side elevation view thereof;

FIG. 4 is a front side elevation view thereof;

FIG. 5 is a right side elevation view thereof;

FIG. 6 is a back side elevation view thereof;

FIG. 7 is a top plan view thereof; and,

FIG. 8 is a bottom plan view thereof.

The broken lines shown in the drawings illustrate portions of the cantilever mounted luminaire that form no part of the claimed design. The post portion of the cantilever mounted luminaire is shown with dot-dash-dot break lines in its length. The break lines and the appearance of any portion of the article between the break lines forms no part of the claimed design.

The area between the dash-dot-dot lines represents unclaimed subject matter that forms no part of the claimed design.
